ILLUMINATION LOUVER

James R. Friend, Rolling Hills, Calif.

Application March 28, 1949, Serial No. 83,795

4 Claims. (Cl. 88—57.5)

1

This invention relates to an illumination louver designed to be used in the ceilings of schoolrooms, exhibition rooms, and the like.

A primary object of the invention is to provide a louver, the louver boards of which are stationarily mounted inasmuch as they do not require adjustment and which will receive incident sunlight through a skylight or the like and reflect the light downwardly into the room in a dispersed or distributed manner so that that portion of the room beneath the louver will be adequately illuminated with evenly distributed light.

More specifically, an object of the invention is to provide an illumination louver having the above-mentioned characteristics which is so designed as to properly function through different seasons and which is so designed that it can be easily and economically manufactured and installed.

With the foregoing and other objects in view, which will be made manifest in the following detailed description and specifically pointed out in the appended claims, reference is had to the accompanying drawings for an illustrative embodiment of the invention, wherein:

Fig. 1 is a top plan view of a schoolroom, the ceiling being illustrated as having been removed except at the location of the louver embodying the present invention;

Fig. 2 is a vertical section taken substantially upon the line 2—2 upon Fig. 1;

Fig. 3 is a transverse section through a pair of louvers illustrating diagrammatically the manner in which the light is reflected during spring and fall seasons;

Fig. 4 is a similar view illustrating diagrammatically the manner in which the light is reflected when the sunlight has its minimum inclination; and

Fig. 5 is a similar view illustrating diagrammatically a condition wherein the sunlight has its maximum inclination.

Referring to the accompanying drawings wherein similar reference characters designate similar parts throughout, the reference character 10 indicates generally a schoolroom which is taken as a typical illustration of the manner in which the improved louver can be advantageously employed. The louver embodying the present invention is in no way restricted in its use to schoolrooms but may be employed in any room where an adequate distribution of reflected light is desired. In the schoolroom illustrated a bank of windows 11 has been shown in one

2

wall thereof which may be assumed to adequately illuminate desks or tables adjacent that wall. The opposite wall indicated at 12 however has been shown as having no windows therein so that, in the absence of any correcting means, the space adjacent the wall 12 will be relatively dark. The roof or ceiling of the room is indicated at 13 and has therein a skylight 14 of any conventional or preferred design which is designed to admit light to the room over that portion thereof which is adjacent the wall 12. While sunlight could be permitted to enter the room through the skylight 14, the use of direct sunlight therethrough is objectionable due to its brilliance and due to its heating effect.

The louver embodying the present invention consists of one or more series of louver boards which are stationarily mounted in suitable frames 15 which are installed in the ceiling directly beneath the skylight 14. The lengths of these boards run generally from east to west and while a perfect easterly-westerly direction is not essential to the use of the present invention, advantages of the improved louver are lost if the lengths of the louver boards extend in a north-south direction. Each louver board may be regarded as being curved in a transverse direction and is somewhat thinner adjacent its lower edge than near its top. The under side of each louver board is convexly curved as indicated at 16 with the inclination of this curvature gradually increasing from the bottom edge of the board upwardly so that near the top of the under surface of the board the surface is inclined to the horizontal to a greater extent than it is adjacent the bottom edge of the board. The upper surface of each board is generally concave and is so formed by three contiguous flat surfaces being indicated at 17, 18, and 19. The inclinations of these surfaces to the horizontal progressively increase from the lowermost surface 17 to the uppermost surface 19. Thus, as illustrated, the inclination of the surface 17 is approximately 45° to the horizontal, the inclination of the surface 18 is approximately 60°, and the surface 19 closely approaches, but is not perfectly, vertical. The top edge of the board is beveled off as at 20, the bevel being approximately 60° to the horizontal.

The boards are spaced from each other so that the vertical projection of one board is but slightly spaced from the vertical projection of adjacent boards.

The improved louver is designed to be used under all conditions of sunlight throughout the

55

year without requiring any adjustment. Some slight modification or adjustment of the shaping of the louver boards may be necessary in different latitudes. However, by way of illustration in the latitude of Los Angeles, California, the minimum inclination of sunlight in the winter is approximately $32\frac{1}{2}^\circ$ whereas the maximum inclination during the summer is approximately 79° . Figure 4 illustrates sunlight encountering the louver boards during the winter wherein the incident light from the sun has an inclination to the horizontal of approximately $32\frac{1}{2}^\circ$. Under these circumstances the incident light will encounter the concave side of each louver board against the uppermost surface and only a portion of the surface 18. That portion of the light which encounters the surface 18 has an angle of incidence thereto of approximately 90° so that much of this light will be reversely reflected thereby as indicated by the arrow 21. That light which encounters the surface 19 will be reflected thereby over the under surface 16 of the adjacent board which, due to its convexity, will reflect the light downwardly into the room with considerable dispersion so as to distribute the light from the wall 12 over approximately one-half of the room.

In the other extreme condition illustrated in Fig. 5, the incident light encounters the louver boards at an angle of approximately 79° to the horizontal. This incident light reaches all three surfaces 19, 18, and 17 and is reflected thereby against the under side 16 of the adjacent louver boards. This surface reflects the light downwardly and due to the convexity causes considerable dispersion as is illustrated diagrammatically in this figure. In the intermediate condition, which is illustrated in Fig. 3, the incident light encounters the louver boards at an angle to the horizontal which is between the two extreme conditions depicted in Figs. 4 and 5. Thus, as illustrated in this figure the light may encounter the entire surface 19, the entire surface 18, and a portion of the lower surface 17. The light reflected from the upper surface 19 may be reflected thereby into the room without being reflected by the surface 16. That light which is reflected by the surface 18 will be reflected thereby against the surface 16 and reflected thereby downwardly into the room with some dispersion due to the convexity of the under surface 16. That light which encounters the surface 17 may be reflected back and forth several times between the surface 17 and the surface 16 but will ultimately be reflected by the surface 16 downwardly into the room with considerable dispersion.

It will be appreciated from the above-described construction that the improved louver never permits direct sunlight to pass through the skylight 14 and directly into the room but that the light is always reflected at least once. Most of the light that encounters the upper surface of a louver board will be reflected thereby onto the under surface 16 of the adjoining board which is so arranged as to reflect the light downwardly and to disperse or distribute it. It will, of course, be appreciated that in different latitudes that the maximum and minimum inclination of the sunlight which is incident to the louver will vary and that slight changes in the exact inclinations of the surfaces 17, 18, and 19 and of the curvature of the surface 16 may be necessary in order to have the louver operate to the best advantage. While it would be possible to form the upper surfaces of the boards in the form of a smooth trans-

verse curve similar to the curve 16, the use of contiguous flat surfaces 17, 18 and 19 is preferable from the manufacturing standpoint in that it is relatively easy to give the board the shaping illustrated with conventional woodworking machines, it being understood that these louver boards are generally formed of wood.

From the above described construction it will be appreciated that the improved illumination louver can be easily and economically manufactured and installed and that when installed the louver boards may remain stationary. However, they are so designed as to automatically receive and reflect light into the room under all conditions from the extreme in winter to the extreme in summer. That light which is reflected into the room is adequately dispersed or spread over a sufficient portion of the room as to adequately supplement the lighting available through the windows 11.

Various changes may be made in the details of construction without departing from the spirit and scope of the invention as defined by the appended claims.

25 I claim:

1. An illumination louver having a series of substantially parallel opaque louver boards each of which is transversely inclined and which is characterized by having on the upper sides thereof a series of contiguous flat surfaces progressively increasing in inclination from bottom to top and having on the under sides thereof convexly curved surfaces arranged to receive light reflected from the flat surfaces and reflect downwardly with dispersion.

2. An illuminating louver having a series of substantially parallel louver boards, each of which is transversely inclined and which is characterized by having on the upper side thereof a series of three or more contiguous flat surfaces progressively increasing in inclination from bottom to top and having on the under side thereof a convexly curved surface arranged to receive light reflected from the flat surfaces and reflect downwardly with dispersion.

3. An illuminating louver for conducting sunlight into a room comprising a series of substantially parallel louver boards arranged in a generally east to west direction, each of the boards being transversely inclined and being characterized by having on the upper side thereof a series of at least three contiguous flat surfaces progressively increasing in inclination from bottom to top and having on the under side thereof a convexly curved surface extending from the bottom edge upwardly through a major portion of the width of the boards, each board having a flat bevel at its top connecting the top of the convex surface with the top of the uppermost flat surface, the boards being arranged sufficiently close together so that direct sunlight cannot pass therebetween without being reflected at least once and the boards being so arranged that most of the sunlight encountering the flat surfaces will be reflected thereby to the convex surface of the adjoining board and reflected downwardly thereby with dispersion.

4. An illumination louver having a series of substantially parallel louver boards each of which is transversely inclined and which is characterized by having on the upper sides thereof a series of three or more contiguous flat surfaces progressively increasing in inclination from bottom to top and having on the under side thereof a convexly curved surface arranged to re-

ceive light reflected from the flat surfaces and reflect downwardly with dispersion, the louver boards being characterized by increasing in thickness from their lower edges upwardly.
